UNITED STATES PATENT OFFICE.

WALTER SYDNEY ROBERTS, OF ORMSKIRK, AND JOSEPH HALLAM BURTON, OF LIVERPOOL, ENGLAND, ASSIGNEES OF ONE-THIRD TO THE RAILWAY SIGNAL COMPANY LIMITED, OF LONDON, ENGLAND, A CORPORATION OF GREAT BRITAIN.

TRAFFIC CONTROLLING APPARATUS FOR RAILWAYS.

Application filed May 27, 1926, Serial No. 112,039, and in Great Britain May 18, 1925.

This invention relates to traffic controlling apparatus for railways and the like of the kind in which tokens are employed as the authority for a train proceeding over a particular section of the track.

Systems of control of this character are now extremely well known and comprise essentially control instruments containing the tokens provided at each end of the section of track to be controlled, the delivery of a token from the instrument at one end of the section being arranged to be effected only by the co-operation of an operator at the other instrument. The two instruments are connected by one or more line wires serving to transmit bell or other signals between the two operators, these wires also transmitting electric current controlling the delivery of tokens from the instruments under predetermined conditions.

The tokens employed in such systems are of various different forms such as staffs, tablets and the like, and when delivered from the token instruments may in some cases be employed for releasing or operating various elements or devices affecting the traffic to be controlled such as points, signals, swing bridge operating mechanism, devices for switching out intermediate block sections, and the like.

As the possession of the token gives full authority for travel within the section to a train or vehicle, as well as when inserted in the token instrument enabling another token or tokens to be obtained from the same or another instrument, it is of primary importance that the token itself should be difficult to counterfeit, and this is also very necessary in order to prevent the devices or elements above referred to when arranged to be actuated by the token, from being improperly operated without the use of the proper token.

The form of the token and consequently the form of the aperture in these devices or elements into which the token is inserted should also obviously be such as to prevent the devices or elements from being operated without the use of a token at all as, for

instance, by picking the lock of the device or element. It is found in practice that some forms of token are unsatisfactory in these respects, owing to the simple shape of the token rendering it not difficult to reproduce, while the aperture in the devices or elements for the accommodation of the token is of considerable size.

Arrangements have previously been proposed for overcoming the above disadvantages as regards the control elements or devices, by providing these with special forms of key operated locking mechanism of the type embodying spring controlled plungers with corresponding keys, these keys being either attached to or formed on a token of the staff or other usual type, or being separate therefrom but arranged to be rendered available by obtaining a staff or tablet from the token instrument.

According to the principal feature of the present invention, the token itself takes the form of a key either wholly or partly, the key token or key portion of the token co-operating with corresponding locking mechanism on the token instrument, whereby the token can only be issued by or returned to the instrument in the case of proper correspondence between the key and the locking mechanism.

The individual characteristics of the key and locking mechanism which thus replace those of other forms of token or supplement these, thus provide increased security as the key form enables a very large number of different "changes" to be readily obtained, and is particularly compact, the locking mechanism on the token instruments being also simple, compact and difficult to tamper with.

The invention is illustrated by way of example in the accompanying drawings of which—

Figure 1 is a view in front elevation of a token instrument embodying one form of the invention,

Figure 2 being a view thereof in sectional side elevation.

Figures 3 and 4 are views in sectional end

and side elevation respectively of the locking mechanism of the instrument shown in Figures 1 and 2.

Figures 5 and 6 are views similar to Figures 3 and 4 respectively of the locking mechanism of a token instrument in which unidirectional tokens are employed, these figures showing the locking mechanism of the instrument at one end of a section of the track, and

Figures 7 and 8 being corresponding views of the locking mechanism of the instrument at the other end of the track.

Referring now first to the construction shown in Figures 1 to 4 inclusive, which illustrates the invention as applied to a token instrument for "absolute" working, in which, when a token has been obtained from the instrument at either end of the section, another token cannot be issued until the first token has been returned to one or the other of the instruments, the element controlling the insertion of the token consists of a rotating lock barrel 1 provided with a key hole aperture 2 adapted to accommodate a key token 3 when the latter is being inserted into, or withdrawn from the instrument. The lock barrel 1 also comprises a second key aperture 4 adapted to accommodate a key token when the latter is being transferred to or withdrawn from the token receptacle 5 of the instrument. The receptacle 5 is provided with a number of passages 17 to accommodate the key tokens, and with suitable ribs 18 for engaging with the token 3 between the collars 6 on the spindle or shank of the token 3, so as to prevent the removal of the tokens directly through the front of the receptacle 5. One of these ribs is cut away as indicated at 19 opposite the aperture 4 in the lock barrel 1 in order to permit a token contained in the receptacle to be inserted into the aperture 4. It will thus be seen that a token 3 contained in the receptacle is located in one or the other of the passages 17, the corresponding portion of the rib 18 lying between the collars 6 on the token so that it is impossible for the token to be moved axially in either direction. In order to withdraw the token, it is displaced laterally along the passage or passages 17 until the token is opposite an opening 20 (Fig. 1) at the middle of the upper passage 17. The token being moved upwards into the opening 20, the outer collar 6 on the token is then opposite the cut-away portion 19 of the uppermost rib 18 so that the token can now be pushed axially inwards to enter the aperture 4 in the lock barrel. The lock barrel 1 is adapted to rotate within a barrel casing 8, as clearly shown in Figures 2 and 4. A portion 9 of the token 3 adapted to enter the aperture in the lock barrel 1 is provided with V-shaped

indentations, a rib 10 being provided for preventing the token from being tilted in a vertical plane.

The locking elements of the mechanism comprise a set of spring-controlled plungers 11 arranged in the casing 8, and a corresponding number of aligned locking plungers 12 in the lock barrel 1. The plungers 11 and 12 correspond to the key hole aperture 2, a corresponding set of spring controlled plungers 13 and locking plungers 14 being provided correspondingly to the key hole aperture 4. The lock barrel 1 is also provided with a set of intermediate plungers indicated at 15.

It will be seen that when the key token 3 is inserted in the aperture 2, as shown in Figure 4, the portion 9 of the token will raise the locking plungers 12 into the position shown in which the lower ends of the plungers 11 are flush with the cylindrical surface of the lock barrel 1, the plungers 13 being moved into a corresponding position by the action of the lower edge of the portion 9 of the key token acting upon the upper ends of the intermediate plungers 15. In these circumstances the lock barrel 1 is evidently released, and is free to be rotated within the barrel casing 8. In a similar manner the insertion of the key token into the key hole aperture 4 will release the plungers 13, and by transmitting movement through the intermediate plungers 15 to the upper plungers 12 will unlock the barrel 1 to permit its rotation. When, however, neither of the key apertures 2, 4 in the barrel 1 is occupied by a key token the locking plungers 11 and 13 will enter the lock barrel 1 and prevent its being rotated. It will be understood that the portion 9 of the key token 3 may be of any desired form other than that illustrated, and may, for example, be provided with notches or indentations on both edges, in which case the lengths of the intermediate plungers 15 will be determined accordingly.

The lock barrel 1 when released as above described is rotated by means of the key token through 180°, whereupon the plungers 12 will evidently come opposite to the plungers 13, the plungers 14, in turn, coming opposite to the plungers 11. The inner ends of the plungers 12 and 14 may be coned or bevelled, as shown, in order to facilitate the insertion and withdrawal of the key token, this construction at the same time facilitating the release of the barrel in spite of slight inaccuracies in the location and formation of the plungers and cylindrical apertures in which they operate.

The locking barrel 1 is mounted upon a shaft or spindle 16 by means of which the motion of the barrel is controlled by a locking mechanism, not shown, this mechanism

being electrically released by current transmitted from one instrument to the other in the manner usual in connection with token instruments and not forming part of 5 the present invention.

Referring now to Figures 5, 6, 7 and 8 the invention is illustrated as applied to a token instrument adapted for a uni-directional system of token operation, in which 10 two distinct forms of token are arranged to be employed in each block section, namely, one for each direction of travel within the section. Assuming a section A—B the A instrument comprises a lock barrel 102 (Figs. 5 and 6) and the B instrument a lock barrel 103 (Figs. 7 and 8); the token for the section B—A is indicated at 104, and as for the section A—B at 105, the two tokens being essentially different from one 20 another. The A—B token is capable of being withdrawn from or returned to the A instrument, but although capable of being inserted in the B instrument cannot be withdrawn therefrom, the reverse conditions applying 25 to the token B—A. It will be observed that two of the notches or indentations on the tokens 104, 105 are similar to one another, for instance the indentations indicated at 30 106, the other two indentations being transposed so that the indentations 107 are similar to one another, as are the indentations 108. The locking plungers of the lock barrels corresponding to the indentations 108 are omitted in the case of each of the barrels 35 102, 103, and the lengths of the intermediate plungers in the lock barrels are such that while the token 104 can be inserted into either of the key apertures in the lock barrel 103, and when thus inserted will free the 40 lock barrel, this key token when inserted in the lower key aperture of the lock barrel 102 will not release the locking plungers corresponding to the upper key aperture. In order to permit, however, the rotation of the 45 lock barrel 103 when the key token 104 is inserted therein, in spite of the locking plungers not being properly operative, a flat groove 109 is provided, so that the barrel 103 in turning in a counter-clockwise direction will force the plungers into their 50 proper releasing positions. In the event, however, of an attempt being made to rotate the barrel in the opposite direction the plungers will hold the barrel locked and thus prevent the issue of the token. Similar arrangements are provided in the case of the barrel 102 for permitting the insertion of the token 105 into the token receptacle through this barrel, while preventing the 55 re-issue of this token.

The tokens of which the re-issue is prevented as above described are transferred to the other instruments by means of magazines of any suitable construction.

60 Having now described our invention,

what we claim as new and desire to secure by Letters Patent is:—

1. In railway traffic controlling apparatus the combination of a token instrument comprising a receptacle for tokens, a plurality of tokens, a rotatable element for transferring one of said tokens from the exterior to the interior of said receptacle, and vice versa, a plurality of locking plungers for controlling the rotation of said element, and means constituted by a portion of each token for releasing said locking plungers. 70

2. In railway traffic controlling apparatus the combination of a token instrument 80 comprising a receptacle for tokens, a plurality of tokens, a rotatable element provided with a pair of key hole apertures, one of said apertures being normally within said receptacle and the other normally without said receptacle, a plurality of locking plungers for controlling the rotation of said element, and means constituted by a portion of each of said tokens for releasing said locking plungers. 90

3. In railway traffic controlling apparatus the combination of a token instrument comprising a receptacle for tokens, a rotatable element, a plurality of locking plungers for controlling the rotation of said element, 95 and means constituted by a token in the form of a key for first releasing said locking plungers, and subsequently rotating said element to transfer said token from the exterior to the interior of said receptacle, and vice versa. 100

4. In railway traffic controlling apparatus the combination of a token instrument comprising a receptacle for tokens, a plurality of tokens, a rotatable barrel having 105 an eccentrically located aperture therein for containing one of said tokens, a plurality of locking plungers for retaining said barrel in an angular position in which said aperture is within said receptacle, and means 110 constituted by a portion of said token for releasing said plungers to permit the rotation of said barrel to a position in which said aperture is without said receptacle.

5. In railway traffic controlling apparatus the combination of a token instrument comprising a receptacle for tokens, a plurality of tokens, a rotatable barrel provided with a pair of key hole apertures, one of said apertures being normally within 120 said receptacle and the other normally without said receptacle, two sets of locking plungers for preventing the rotation of said barrel, and corresponding respectively to said apertures, means constituted by each of said tokens for releasing one set of plungers when inserted in one of said apertures, and means operated by said token when thus inserted for indirectly releasing 125 said other set of plungers. 130

6. In railway traffic controlling apparatus the combination of a token instrument comprising a receptacle for tokens, a plurality of tokens, each in the form of a key,
5 a rotatable barrel having a pair of eccentrically arranged key hole apertures, a set of locking plungers corresponding to each

of said apertures, and a third set of plungers arranged in said barrel intermediate said apertures.

10 In testimony whereof we have hereunto set our hands.

WALTER SYDNEY ROBERTS.
JOSEPH HALLAM BURTON.
